Des. 1282

Garrison Smith & Henry Bonner of Philadelphia Pa,
Assignors to
Leibrandt & M. Dowell, of same place.
Letters Patent No 1282 Dated July 3-1860.

The schedule referred to in these Letters Patent and making part of the same.

To all whom it may concern:

Be it known that we, Garrison Smith & Henry Brown, both of the City of Philadelphia, and State of Pennsylvania, have invented or produced a new and original Design for a Cooking Stove; and we do hereby declare that the following is a full and exact description of the same, reference being had to the annexed drawings, making a part of this Specification, in which -

Figure 1, is a perspective representation of the stove, and

Figures 2 & 3, transverse sections of the mouldings, respectively, of the top & bottom plates thereof, like letters when on the different figures, indicating the same objects.

The nature of our invention or production consists of certain curved ornaments on the plates constituting the sides and front of a cooking stove, and the doors thereof - and also of mouldings around the edges of the top and bottom plates - as hereinafter described, which stove for the purpose of nominal distinction, we call the "Herald".

In the drawings, A, represents the plate, and B, the door of the left side of the said Stove, - the ornaments on the right or opposite side, though not seen in the drawing, correspond with those on the left; A, in each particular, C, represents the front plate of the said Stove; D, D, its doors, L, the top plate, and M, the bottom plate.

The side plate, A, is ornamented with the figures e, f, g, and its door, B, with the figure h, all as seen in figure 1. The ornamentation (g) is, in the right hand side of the stove, on a door instead of on the plate A, but in the same relative position.

The front plate C, is ornamented with the head i, surrounding the word or name "Herald", which is in raised letters, and directly above this, the damper i', projects forward as seen in figure 1.

The two doors, D, D, are each ornamented with the figure k, as seen in the drawing.

The edges of the top plate, L, are finished with the moulding n, - a transverse section of which is shown by figure 2.

The edges of the bottom plate, M, are finished with the moulding o, - a transverse section of which is shown by figure 3.

All are intended to be cast of metal and, therefore, the ornaments specified are carved in relief in such a manner or form as to be adapted for being readily withdrawn from the sand, in moulding in the usual manner.

What we claim herein as our invention or production and desire

to secure by Letters Patent is. -

1st. The ornamentations e, f & g. on each of the two side plates (A), as described.
2nd. We claim the ornamentation (h) on each of the two side doors (B), as described.
3rd. We claim the ornamentation i; the letters forming the name "Kerald", and the projecting form of the damper (i'), respectively on the front plate (G) as described.
4th. We claim the ornamentation (K) on each of the two front doors (D).
5th. We claim the moulding (n) around the top plate (L); and
6th. We also claim the moulding (o) around the bottom plate (M);
all as and for the purpose set forth and specified.
